UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

FEEDING MECHANISM FOR CONFECTIONERY MACHINES.

Application filed October 25, 1921. Serial No. 510,325.

To all whom it may concern:

Be it known that I, ALONZO LINTON BAUSMAN, a citizen of the United States, residing at Springfield, in the county of Hampden 5 and State of Massachusetts, have invented new and useful Improvements in Feeding Mechanism for Confectionery Machines, of which the following is a specification.

This invention relates to improvements in 10 feeding mechanism for confectionery machines and, while capable of other applications, it is particularly advantageous for use in connection with depositors, especially where the latter are used for making deposits 15 on previously formed articles, as for example on biscuits, cakes and the like, which may or may not be subsequently coated.

The invention has for one object to provide an article feeding mechanism which includes a feed belt and a series of feed bars 20 movable over the belt, each feed bar having notches in its leading edge to engage the articles and center or align them properly, together with means for driving the feed belt 25 and feed bars, characterized in that the speed of the feed belt is somewhat less than that of the bars, so that the belt exerts a constant dragging effect upon the articles to hold them against the notched walls of the 30 feed bars.

Another object of the invention is to provide in a feeding apparatus of the class described, a specifically improved feed bar, characterized in that a series of notches are 35 provided in its leading edge to engage and center articles and a series of suitably shaped recesses are also provided in its trailing edge to receive the leading ends of the articles, whose other ends are engaged and fed by the 40 leading edge of the next succeeding feed bar, whereby relatively long articles may be held in the desired positions against sidewise displacement while being fed.

Another object of the invention is to provide, in connection with the feed belt and feed bars of the mechanism described, means 45 for tapping the edge of the feed belt or agitating it in a transverse direction to assist in directing the articles into the notches in the feed bars.

Another object of the invention is to provide a depositing mechanism, by means of which various substances, such as marshmal-

low for example, may be deposited on articles such as cakes, cookies and the like; a 55 coating machine whereby the articles, upon which the deposits have been made, may be coated, as with chocolate or the like; conveying means to carry the articles through the depositing mechanism, auxiliary feeding means to center and align the articles 60 properly to receive the deposits; and conveying means to carry the articles after they leave such mechanism to a coating machine, the last-named conveying means being interposed between the depositing and coating machines to create a substantial interval 65 between the times of deposit and coating during which interval the deposited substances will have time to partially dry or harden. 70

Another object of the invention is to provide a depositor and a coating machine with conveying means to carry articles to and through each, together with an auxiliary 75 endless conveying means having a series of transverse feed bars notched along their leading edges, said endless conveying means arranged with one lap of travel in parallel relation with and above a portion of the first conveying means, so that the feed bars align 80 the articles properly for the deposit and after the deposit leave the first conveying means, leaving the articles all properly aligned transversely and spaced longitudinally for the coating machine. 85

A further object of the invention is to provide in a depositor which is normally intended to make a deposit on an article while at rest and has feeding means operable step-by-step for this purpose, an auxiliary feeding means movable simultaneously and substantially at equal speed with the first feeding means for holding the ends of relatively long narrow articles in alignment with the depositor nozzles and against transverse displacement, together with mechanism operable in conjunction with said feeding means, whenever desired, to cause them to move during the deposits for the purpose of spreading the deposits along the entire length of the 90 articles. 95

Other objects and advantages will appear in the following description and in the illustrative embodiment of the invention in the accompanying drawings in which,—

Figs. 1^a and 1^b are side elevational views

showing together, when joined along the line $a-a$, a complete side elevational view of an apparatus embodying the invention;

Fig. 2 is a sectional plan view taken on the line 2-2 of Fig. 1^a;

Fig. 3 is an enlarged fragmentary plan view showing in detail the feeding bars;

Fig. 4 is a sectional elevational view taken on the line 4-4 of Fig. 3;

Fig. 5 is a fragmentary, and considerably enlarged, plan view showing the means for connecting the ends of the feed bars to their endless propelling means;

Fig. 6 is a large scale plan view of a portion of a feed bar, showing in complete detail the preferred construction of the notches and recesses therein;

Fig. 7 is a cross-sectional view taken on the line 7-7 of Fig. 1^a; and

Fig. 8 is a fragmentary top plan view of the right-hand end of the depositor shown in Fig. 1^b.

Referring to these drawings: the feeding mechanism is usually used in connection with a depositor, which may be of any suitable type, and, as an illustrative example of one such type, there has been shown in somewhat conventional form in Figs. 1^a and 1^b a depositor of the same general type as that disclosed in my prior U. S. Letters Patent No. 1,169,602, granted Jan. 25, 1916. It includes a hopper *b* for containing the substance to be deposited, a series of transversely spaced pump cylinders *c* having suitable pistons therein and outlet nozzles *d* through which the material from hopper *b* is discharged upon articles supported therebelow, all in a manner too well known in the art to require detailed description here.

This hopper *b* is supported from and extends between two laterally spaced side frames *e* in which a main driving shaft *f* is mounted.

From this shaft, the depositing mechanism is operated in a manner disclosed in the above-mentioned patent.

In conjunction with the depositor just described, an auxiliary frame structure is employed for the purpose of supporting the usual as well as the auxiliary feeding mechanism. This structure includes two channel irons 10 disposed between the side frames *e* and pivotally mounted, near one end, in laterally spaced relation on a rod 11. The ends of the latter extend through vertical slots 12 in frames *e* and each such end is supported by a screw 13 rotatably mounted in a lug 14 on frame *e* from which lug the screw depends and extends diametrically through the end of the rod, having a threaded connection therewith. By this arrangement, the channels 10 may be lifted or lowered at one end for a purpose which will later appear. The channels 10 extend in spaced parallel relation to and beneath the depositing mechanism and a considerable

distance beyond the latter, being supported at their other ends by transversely spaced uprights 15, which in turn are supported upon the floor upon which the depositor frames *c* rest. The uprights 15 extend above channels 10 and their upper ends are connected by two longitudinal members 16 to the upper ends of two uprights 17, which are secured to channels 10 near the described rod 11.

Near one end (the left as viewed in Fig. 1^a) of the channels 10, a receptacle 18 is provided to receive articles, such as biscuits, cakes, cookies and the like which are to be fed to the depositor. This receptacle is supported by and above the channels 10 by brackets 19.

For the purpose of supporting the feed belt, to be later described, a table is provided, consisting of two sections 20 and 21, which are slightly wider than the feed belt and may be reenforced, if desired, by longitudinally disposed channels 22 secured to the under sides thereof. One of these sections, as 20, has secured to each side at one end a bracket 23 which is pivotally connected at 24 with the adjacent receptacle supporting bracket 19. The other end of this table section is pivotally connected at its other end to the transversely spaced upper extremities of a fork 25 and centrally attached to the latter is a depending rod 26. On the lower end of the latter is a fork 27 which straddles shaft *f* and above this fork is a roll 28 which rests upon the periphery of a cam 29 fixed to the shaft. One revolution of the latter effects one complete cycle of operations of the depositor and, as usual, is arranged to actuate the feeding mechanism and depositing mechanism alternately, each being at rest while the other operates. The cam 29 is so constructed and is fixed to shaft *f* in such angular relation with respect to other parts fixed thereon, as to hold the table section 20 in its lowered and illustrated position during the operation of the feeding mechanism; to raise the table at the end of such operation and before operation of the depositing mechanism; to hold the table in lifted position during operation of the last-named mechanism; and to drop back to its lower position after operation of the depositing mechanism and before operation of the feeding mechanism.

The second table section 21 is supported stationarily although in an adjustable manner. Thus, it is pivoted at 30, at that end adjacent section 20, to brackets 31 secured to channels 10 and is supported at the other end by brackets 32, in each of which screw 33 is mounted. The ends of these screws rest on channels 10 and by turning them the delivery end of section 21 can be raised or lowered for a purpose which will appear.

- The usual and primary feeding mechanism includes a feed belt 34, the upper lap of which passes over table sections 20 and 21 and is thereby supported against sagging.
- 5 This belt is driven by a roll 35 which is fixed to a shaft 36 and the latter is rotatably mounted near each end in a bearing formed in a member 37. Each member 37 is secured, as by bolt and slot connections indicated
- 10 at 38 in Fig. 2, to a channel 10 so as to be longitudinally adjustable relatively thereto for the purpose of tensioning belt 34. A rod 39 is fixed to one end of each member 37 and extends loosely through a bracket 40
- 15 fixed to a channel 10. The free end of rod 39 is threaded and provided with a thumb nut 41, by means of which the members 37 may be adjusted. The belt 34, at the other end of its upper lap of travel, passes
- 20 over a very small shaft 42 mounted in bearings 43. Each of the latter is fixed to the end of a bracket 44, secured to channels 10, similarly to members 37, for longitudinal adjustment, which may be effected by turning
- 25 screws 45 threaded into brackets 44 and abutting brackets 46 fixed to channels 10.
- The feed belt 34 is driven from an intermittently operable shaft 47, which is connected by a chain 48 and suitable sprockets
- 30 (Fig. 2) to the shaft 36 already described. Shaft 47 is rotatably mounted in the depositor side frames *e* and passes through openings 49 in the channels 10, one of which openings is indicated in dotted lines in Fig.
- 35 1^a. Fixed to one end of shaft 47 is a ratchet 50 having a relatively few (seven as shown) teeth and pivotally mounted intermediate its ends on shaft 47 is a lever 51, the upper end of which carries a pawl 52 to engage the
- 40 ratchet. The lower end of lever 51 has a slot 53 to receive a stud 54 connected, preferably adjustably as indicated, to one end of a link 55. The stud 54 may be fastened to lever 51 in various positions of adjustment for
- 45 the purpose of varying its throw, all in the customary known manner. Link 55 is pivotally connected at its other end to a lever 56, pivoted at 57 to frame *e* and this lever is oscillated by a crank 58 fixed on shaft *f*
- 50 and a link 59 which connects the crank to the lever. The connection of the link 59 to lever 56 is preferably adjustable, as indicated. By means of the adjustments described, it is possible to get the desired
- 55 throw of pawl 52, so that on each revolution of crank 58 the ratchet 50 will be turned through an arc equal to the distance between successive teeth thereof, and such throw is arranged to move belt 34 a linear
- 60 distance equal to that desired between the centers of successive rows of cakes or the like.
- In conjunction with the feeding mechanism just described, I employ an auxiliary feeding mechanism, which consists of an
- endless series of transverse feed bars 60, a few of which are indicated conventionally in Fig. 2. These feed bars are connected at their ends and extend between two endless chains 61 which travel over sprockets 62 mounted on shafts 63, rotatably mounted in the auxiliary frame structure heretofore described, and over sprockets 64 (Fig. 1^b) fixed on a shaft 65 rotatably supported by the uprights 17. The sprockets described support the chains 61 so that in their lower lap of travel they move substantially parallel to the belt 34 in its upper lap of travel. As shown, the chain 34 in its lower lap of travel has some sag and the sprocket 64 is 70 purposely so located that the chains 61 gradually rise away from belt 34 near the delivery end thereof. The sprocket 64 is the driving sprocket and its shaft 65 carries a spur gear 66 which meshes with a like gear 67 to which is fixed a sprocket 68. The gear 67 and sprocket 68 rotate upon a stud 69 mounted in a bearing secured to upright 17. The sprocket 68 is connected by a chain 70 to a sprocket on shaft 47, whereby the chains 61 are driven simultaneously with belt 34 and so that the lower lap of travel of the chains and the upper lap of travel of the belt are in the same direction. The driving connections described are designed 80 to drive the chains 61 and belt 34 at substantially equal speed, although preferably the belt is arranged to travel slightly slower than the chains.
- The feed bars 60 are shown in full detail in Figs. 3 and 6. As there shown, these bars are fastened at their extremities to lugs 72 on chains 61 and rest upon belt 34. In Fig. 3, these bars are indicated as travelling in the direction of the arrow toward the depositor nozzles *d* and their leading and trailing edges are indicated at 73 and 74 respectively. The leading edge of each bar 60 is provided with a series of notches 75, in which the articles *x*, such as biscuits, cakes, cookies and so forth, may be received and held properly positioned in line with the nozzles *d*. The preferred construction of these notches is shown in Fig. 6, and, as indicated, each notch has two walls 76 which converge away from the edge 73 and are joined by a central rounded wall 77. The two walls 76 together act to position an article *x* and hold it against sidewise displacement and each of these walls will function, within limits, to move improperly positioned articles, such as *x'*, into the desired position, this operation being effected by a cam action of the moving inclined wall 76 on the article.
- The trailing edge of each feed bar 60 is also provided with a series of recesses 78, each lying opposite one of the notches 75. These recesses are provided to supplement the notches 75 and assist them in holding

relatively long articles, such as that shown at x'' in Fig. 3, in proper position. As illustrated, the rear end of the article x'' is positioned in a notch 75 of one feed bar 60 and the front end thereof lies in the recess 78 of the preceding feed bar.

To assist in directing articles, such as x , into the recesses 75, means are provided for agitating the feed belt 34 transversely and 10 such means will now be described with particular reference to Figs. 1^a, 2 and 7. Rotatably mounted in bearings 79 fixed to one of the channels 10 is a shaft 80 which carries two longitudinally spaced ratchet wheels 81. Shaft 80 is driven by bevel gears 82 from the shaft 36, the driving means for which have already been described, and has a bearing in the described adjustable bracket 37. The arrangement is such that as the 20 latter is moved, the shaft 80 and gears 82 move with it, the shaft sliding through the ratchets 81, after the set screws 83, by means of which they are held in place, are loosened. Slidably mounted on the channels 10, as best 25 shown in Fig. 6, are slide bars 84, one for and opposite each ratchet 81. A spring 85 yieldingly draws each bar 84 toward its ratchet. Fixed to and upstanding from each bar 84 are two brackets 86 and 87 disposed in longitudinally spaced relation on bar 84 and arranged on opposite sides of the 30 table 20. The two brackets 86 are connected by a bar 88 which parallels the edge of belt 34 and rests upon table 20 closely adjacent 35 to such edge. A similar bar 89 connects the brackets 87. A screw 90 is adjustably held in each of the brackets 87, as indicated in Fig. 7, and one end thereof is adapted to cooperate with the adjacent channel 22 as a 40 stop to limit the extent of return movement effected by spring 85, whereby the degree of movement of bar 84 and thus the degree of agitation thereof may be varied, as desired. As the ratchets rotate, the bars 84 are moved 45 rapidly back and forth and one bar, as 88, strikes the edge of belt 34 on one stroke and the other bar as 89, strikes the other edge of the belt on the other stroke.

The depositor normally discharges, 50 through its nozzles d , measured charges of confection, such as marshmallow for example, upon the articles during an interval or rest of the feeding mechanism. A deposit so made is conventionally indicated at 55 y in Fig. 4 and in the case of small and approximately round articles, such as the cake x there represented, the deposit, made in the manner described, will spread sufficiently to cover the area of the cake. However, with 60 long articles, such as shown at x'' in Fig. 3, the deposit would not be distributed over its entire area, as desired, unless some other means were employed for the purpose. To this end, I provide means for effecting a 65 relative movement between the articles and

the depositor nozzles during the time of deposit and, conveniently although not necessarily, this result is effected by moving the feeding mechanism already described. Such mechanism moves the belt 34 and bars 60 by steps equal to the spacing of the bars, as by the distance r , indicated in Fig. 3. After such mechanism ceases to move the belt and bars, another mechanism may be employed to move the belt and bars during the interval of deposit sufficiently to spread the deposited confection, such as the distance s . Then when the main feeding mechanism is brought into play, it is arranged to move the articles a distance equal to r minus s . 70 75 80

The auxiliary feeding mechanism includes a second ratchet wheel 91 fixed on the shaft 47, which as described carries the ratchet wheel 50. The ratchet 91 has a large number of small teeth, as indicated in Fig. 1^a. Cooperating with ratchet 91 is a pawl 92 pivoted to the upper end of a lever 93, which is pivotally mounted intermediate its ends on shaft 47. Connected to the lower end of lever 93, preferably adjustably as indicated, is a link 94, which extends to and is pivotally connected to an arm 95 fixed to one end of a rock shaft 96 mounted in and extending between the frames e . Fixed to the other end of shaft 96 is an arm 97 which is connected by a link 98 to the lever 56 already described. By means of the rocker arms 95 and 97, the pawl-carrying levers 51 and 93 are made to rock in opposite directions. That is, while pawl 52 is being moved clockwise to advance ratchet 50, pawl 92 is moving counterclockwise without moving its ratchet. The two pawls then are effective alternately. It will therefore be seen that, 100 after pawl 52 has moved ratchet 50, pawl 92 may then move its ratchet 91 by a step sufficient to cause the feed belt to move a distance such as s and in so doing ratchet 50 is also moved a like step since it is fixed to the same shaft. Therefore, on a succeeding active stroke of pawl 52, the tooth, which it ordinarily would have immediately engaged, 105 will have been moved forward by the operation of pawl 92 so that pawl 52 will travel idly until it catches up with this tooth and therefore will move ratchet 50 only the distance r minus s . The auxiliary feeding mechanism described may be rendered ineffective simply by swinging back pawl 92 110 so that it will not engage its ratchet. 115 120

The adjusting devices 14 and 33 are provided to align belt 34 with another conveyer, to be described, and the adjusting device 45 is provided to permit the delivery end of belt 34 to be moved into close proximity to such conveyer. 125

In many instances, it is desired to coat the articles x after the confectionery substance has been deposited thereon and in 130

such instances the feed belt 34 may be arranged to deliver the articles to a coating machine, wherein they may be enveloped by a coating of material, such as 5 chocolate or the like. For such purposes, a coating machine C may be employed, a portion of which with its conveyor *k* is conventionally indicated in Fig. 1^b. Various types of coating machines may be employed as desired and, as an illustrative example of one suitable type, a coating machine, such as that disclosed in U. S. Letters Patent No. 790,184, granted May 16, 1905, on an invention of Gabriel Carlsson, may be employed. Preferably, however, means are interposed between the depositor and coating machine whereby the deposited confectionery substance is permitted to dry or harden somewhat before 20 it is subjected to the flood of coating material in the coating machine C. To this end, I interpose between the two machines a conveyor, consisting of an endless belt 100 which is driven by a roll 101 mounted 25 in a pedestal 102 and travels over a table 103 supported at one end by said pedestal and adjustably supported at the other end by screws 104 which rest upon a ledge 105 formed on the casing of the coating machine. The roll 101 may be driven in any 30 suitable manner, as for example from the coating machine in the general manner disclosed in U. S. Letters Patent No. 735,890, granted August 11, 1903 to E. P. F. Magneiz.

In operation, the articles are placed in hopper 18, from which they are removed a few at a time by an operator. The articles fall upon belt 34 at or near the point 40 where the latter is agitated and this agitation assists in moving the articles against and into the notches 75 of the feed bars. The operator, stationed at this point, will of course have to attend to the matter of 45 positioning the articles properly, but, in the case of articles generally similar to those shown at *x*, the agitation of belt 34 assists the operator in this work to a considerable degree. Articles like those shown at *x''* have 50 to be manually placed in the desired position. Another factor tending to assist in positioning articles, such as *x*, in the notches of the feed bars 60 is the difference in speed between the latter and belt 34, 55 the latter moving somewhat slower to create a dragging effect on the articles and draw them toward the feed bars and hold them there after engagement.

The articles, having been properly positioned, the belt 34 and bars 60 are moved 60 step by step and at the end of each step one row of articles is positioned beneath the depositor nozzles to receive through the latter measured charges of a confectionery substance which is deposited during 65

an interval of rest of the main feeding mechanism. As has been stated, the auxiliary feeding mechanism may be employed to move the articles, particularly when similar to those shown at *x''*, during the 70 time of depositing in order to distribute the deposits in a manner already disclosed. After the deposits have been made, the articles are carried step by step and eventually transferred to belt 103. Previous to this 75 transfer, however, the feed bars gradually lift away from the articles, leaving them properly spaced both longitudinally and transversely for the coating machine C, to which they are eventually carried by belt 80 103, the latter being interposed as described for the purpose of allowing the deposited confection to dry or harden prior to the coating operation.

The invention has been disclosed herein, 85 in an embodiment at present preferred, for illustrative purposes, but the scope of the invention is defined by the appended claims rather than by the foregoing description.

What I claim is—

1. Feeding mechanism for confectionery machines, comprising, supporting means for the articles to be fed, and a series of feed bars movable in spaced parallel relation over said supporting means and adapted 95 to propel the articles thereon, each of said bars having means provided along its leading edge for centering and propelling articles and means provided along its trailing edge for guiding the leading ends of 100 articles centered and propelled by the preceding bar.

2. Feeding mechanism for confectionery machines, comprising, supporting means for the articles to be fed, and a series of feed 105 bars movable in spaced parallel relation over said supporting means and adapted to propel the articles thereon, each of said bars having its leading edge provided with a series of longitudinally spaced notches to 110 engage and center the articles and its trailing edge provided with recesses in which the leading ends of articles propelled by the notched edge of the preceding bar may 115 be received and held against sidewise displacement.

3. Feeding mechanism for confectionery machines comprising, means for supporting the articles during the feeding movement, a series of cross bars movable in spaced relation over said means and each provided 120 along its leading edge with means for centering the articles, and means for agitating the first named means to assist in directing the articles into the centering means.

4. Feeding mechanism for confectionery machines, comprising, a feed belt for the articles to be fed, and a series of feed bars movable in spaced parallel relation over 125 said feed belt and adapted to propel the 130

- articles thereon, each of said bars having its leading edge provided with a series of longitudinally spaced notches to engage and center the articles and its trailing edge provided with recesses in which the leading ends of articles propelled by the notched edge of the preceding bar may be received and held against sidewise displacement.
5. Feeding mechanism for confectionery machines, comprising, a feed belt for the articles to be fed, and a series of feed bars movable in spaced parallel relation over said feed belt and adapted to propel the articles thereon, each of said bars having means provided along its leading edge for centering and propelling articles and means provided along its trailing edge for guiding the leading ends of articles centered and propelled by the preceding bar.
10. Feeding mechanism for confectionery machines, comprising, a feed belt, a series of feed bars movable over said belt and in a path parallel with one lap thereof, each of said bars provided with a series of recesses in its leading edge in which the articles to be fed may be received and centered, means for tapping said belt during its travel to assist in directing the articles into said recesses, and means for moving the feed bars at a speed slightly in excess of that of the feed belt, whereby the feed belt tends to drag the articles into said recesses and hold them there.
15. Feeding mechanism for confectionery machines having a transverse row of nozzles through which measured quantities of confection may be deposited upon articles positioned therebelow, supporting means for the articles upon which they travel to said nozzles, a series of notched feed bars movable over said means and arranged to move the articles in properly spaced relation to said nozzles, and means for agitating said supporting means to assist in directing the articles into said notches.
20. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
25. Feeding mechanism for confectionery machines having a transverse row of nozzles through which measured quantities of confection may be deposited upon articles positioned therebelow, an intermittently movable feed belt, a series of notched feed bars movable with and above the feed belt for carrying the articles to said nozzles, and means operable intermittently with the feed belt for agitating the latter.
30. Feeding mechanism for confectionery machines, comprising, a feed belt, a series of feed bars movable over said belt and in a path parallel with one lap thereof, each of said bars provided with a series of recesses in its leading edge in which the articles to be fed may be received and centered, means for tapping said belt during its travel to assist in directing the articles into said recesses, and means for moving the feed bars at a speed slightly in excess of that of the feed belt, whereby the feed belt tends to drag the articles into said recesses and hold them there.
35. Feeding mechanism for confectionery machines having a transverse row of nozzles through which measured quantities of confection may be deposited upon articles positioned therebelow, supporting means for the articles upon which they travel to said nozzles, a series of notched feed bars movable over said means and arranged to move the articles in properly spaced relation to said nozzles, and means for agitating said supporting means to assist in directing the articles into said notches.
40. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
45. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
50. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
55. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
60. Feeding mechanism for confectionery machines having a transverse row of nozzles through which measured quantities of confection may be deposited upon articles positioned therebelow, a feed belt, a series of notched feed bars movable with and above the feed belt for carrying the articles to said nozzles, and means for agitating said belt.
65. Feeding mechanism for confectionery machines having a transverse row of nozzles through which measured quantities of confection may be deposited upon articles positioned therebelow, an intermittently movable feed belt, a series of notched feed bars movable with and above the feed belt for carrying the articles to said nozzles, and means operable intermittently with the feed belt for agitating the latter.
70. Feeding mechanism for confectionery machines having a transverse row of nozzles through which measured quantities of confection may be deposited upon articles positioned therebelow, an intermittently movable feed belt, a series of notched feed bars movable with and above the feed belt for carrying the articles to said nozzles, and means operable intermittently with the feed belt for agitating the latter.
75. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
80. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
85. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
90. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
95. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
100. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
105. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
110. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.
115. Feeding mechanism for applying a confectionery substance to articles, means for supporting the articles while being fed to the first named means and during the operation of the latter, a pair of endless flexible members mounted to travel in laterally spaced relation and in a closed loop path above the supporting means with one lap of travel substantially parallel and in adjacent relation with the supporting means, and a series of notched feed bars carried by and between said flexible members.

In testimony whereof I have affixed my signature.

ALONZO LINTON BAUSMAN.
